UNITED STATES PATENT OFFICE

LUTHER EDWARD RICE, OF AURORA, INDIANA

SCREENING DEVICE

Application filed October 15, 1928. Serial No. 312,615.

This invention relates to improvements in screening devices, and its general object is to provide a device for vibrating a screen in an extremely rapid manner to prevent material from sticking thereto, with the result the screen can be kept in a relatively clean condition at all times and thereby expeditiously and efficiently perform a screening function.

10 Another object of the invention is to provide a vibratory screening device that will vibrate a screen in a vertical plane, and will not in any way damage the screen or the vibrating means therefor, which is constructed so that it will efficiently operate for a prolonged period of time with minimum repairs and upkeep.

Another object of the invention is to provide a vibratory screening device that is simple in construction and inexpensive to manufacture.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is an end view of one form of my screening device with parts thereof in section.

Figure 2 is a front view thereof.

Figure 3 is a sectional view taken approximately on line 3—3 of Figure 1.

40 Figure 4 is a fragmentary view of a modified form of my device and showing parts thereof in section.

Figure 5 is a vertical sectional view showing the eccentric means for the form of my invention as shown in Figure 4.

Figure 6 is a detail view of the eccentric means per se.

Figure 7 is a similar view of a modified form of screen tapping means.

80 Figure 8 is a perspective view of the rock-

ing hammer which forms a part of the tapping means.

Referring to the drawings in detail, it will be noted that I provide a supporting frame which includes parallel channel bars 1 having secured to the upper surfaces thereof and rising therefrom angle brackets 2 which support and have secured to their upper ends a channel bar 3 arranged to bridge the channel bars 1 as suggested in Figure 4.

Mounted upon and secured to the channel bar 3 adjacent one end thereof is an electric motor 4 having connected to the armature shaft thereof and arranged in alignment therewith a shaft 5.

The shaft 5 is secured to the armature shaft through the medium of a coupling 6 and is arranged through and supported by appropriate bearings 7 disposed in parallelism with each other and secured to the channel bar 3 as best shown in Figure 2. The bearings 7 hold the shaft 5 in true alignment with the armature shaft so that vibration caused by the device will not damage the motor. The free end of the shaft 5 is reduced and terminates in an eccentrically disposed projection 8 which has secured thereto an anti-friction bearing 9 through the medium of a washer and screw bolt as best shown in Figure 3.

Secured to the anti-friction bearing is a sectional housing 10 having extending therefrom a relatively flat arm 11 which has secured thereto the bifurcated upper end of a connecting rod 12. The lower end of the connecting rod 12 is also bifurcated and has arranged in the arms 13 thereof registering vertically disposed slots 14 for a purpose which will be presently apparent.

In Figures 4 to 6 inclusive I have illustrated a modified form of eccentric means and for the purposes of distinction, the shaft which is secured to the armature shaft of the motor through the medium of the coupling 6, is indicated by the reference numeral 15 and also passes through a bearing similar to the bearings 7. However, the shaft 15 is of the same diameter throughout its length and fixed to its free end by a sleeve 16 is a guide housing 17 which has arranged for vertical

slidable movement therein a block 18 formed with a threaded bore.

The block is held in said guide housing 17 by strips 19, and threadedly received in the bore of the block 18 is a screw 20 having one end swiveled in the bottom of the guide housing while its opposite end extends through the top thereof and is provided with a head for receiving a wrench or the like whereby the block 18 can be adjusted as will be apparent. 10 A lock nut 21 is mounted on the screw 20 for retaining the block in its adjusted position.

Formed with the block and extending centrally from its outer face thereof is a bearing stud 22 which receives an anti-friction bearing similar to the bearing 9, and carried by the bearing of the bearing stud 22 is a sectional housing having an arm depending therefrom which likewise receives a connecting rod similar to the rod 12. 15

In the form of the invention just described, namely as shown in Figures 4 to 6, it will be obvious that due to the fact the block 18 is adjustably mounted, the stud 22 can be adjusted to any desired position with respect to the shaft 15 to vary the eccentric position with respect thereto accordingly, while in the form as shown in Figures 1 to 3 inclusive, the eccentric is non-adjustable. 25

30 The screen frame includes strips 23 which are supported upon the lower horizontal portions of the channel bars 1 and held thereon accordingly through the medium of bolts 24 having their heads countersunk in the strips as best shown in Figure 4. The strips have fixed thereto wire cloth 25 and cooperating with the bolts 24 are nuts 26.

Secured to the wire cloth and arranged in superposed relation with respect to each other upon opposite sides of the cloth are clamping means including wood strips 27 which have fixed thereto by bolt and nut connections 28 and a plate 29, a bracket 30 having rising therefrom a lug 31 formed with an opening 45 for receiving the bolt 32 which likewise is received by the slots 14 whereby the bracket is secured to a connecting rod 12 with the result when the motor is put into operation, the screen will be vibrated in a manner whereby 50 the movement thereof will be in a vertical plane.

In order to assist in retaining the wire cloth in a clean condition, I provide a tapping means which includes a bar 33 mounted for 55 slidable movement on the bolt 24 which pass through openings formed in the ends thereof. Disposed upon opposite sides of the bar 33 are coil springs 34 which have one of their end convolutions engaging the bar, while the opposite end convolutions engage the nuts 26 and the nuts 35 secured to the bolts 24 adjacent the ends thereof as shown in Figure 4.

The bar 33 has fixed thereto and rising therefrom a bolt 36 which is held in operative position by a lock nut and has its upper

end disposed in contacting engagement with the plate 29. By this construction, it will be apparent that when the device is put into operation, the plate will engage the bolt 36 and cause the bar 33 to reciprocate on the bolts 24 and thereby the bolt 36 will set up the hammering action against the plate. 70

In Figures 7 and 8 I have illustrated a modified form of cleaning means and in this form I provide a substantially U-shape rocking arm 37 mounted for rocking movement midway its ends to an apertured ear 38 which is fixed to the wood strips by a threaded stud and a nut as shown. 75

The rocking arm has pivotally secured thereto laterally of its pivot connection with the ear, the lower end of a connecting rod 39, while the opposite end of the rod is pivoted to the eccentric stud of the shaft 5. The upper strip 27 has secured thereto and arranged in the path of the ends of the U-shape rocking arm 37, blocks 40. By this construction, the wire cloth will be vibrated by the connection of the rocking arm with the shaft 5, and the rocking arm will also set up a hammering action upon the cloth. 85 90

From the above description and disclosure of the drawings, it will be obvious that I have provided a screening device that may be used for screening any granular material, and performs its intended function in minimum time and with maximum efficiency. 95

It is thought from the foregoing description that the advantages and novel features of my invention will be readily apparent. 100

I desire it to be understood that I may make changes in the construction and in the combination and arrangement of the several parts, provided that such changes fall within the scope of the appended claims. 105

What I claim is:

1. In a screening device, a supporting frame, screening means, a frame for said screening means, vertical reciprocating means for said screening means and having connection with the supporting frame, bolts securing the screen frame to the supporting frame, a bar slidably mounted on said bolts, coil springs surrounding said bolts and yieldably supporting said bar, impact means secured to said bar and rising therefrom, means connected with the vertical reciprocating means and the screening means respectively and being arranged in the path of the impact means whereby a hammering action is imparted to said screening means. 110 115 120

2. In a screening device, a supporting frame, a screening means, a frame for said screening means, bolts for securing the screening means frame to the supporting frame and extending below the supporting frame, a bar mounted for slidable movement on said bolts, nuts secured to said bolts, coil springs surrounding the bolts and having the end convolutions engaging the bar and 125 130

the nuts respectively for yieldably supporting said bar, vertically reciprocating means for said screening means, clamping means secured to said screening means and the vertically reciprocating means respectively, impact means carried by said bar and including a bolt arranged in the path of the clamping means whereby a hammering action is imparted to the screening means.

5 10 In testimony whereof I affix my signature.
LUTHER EDWARD RICE.
